(57) **CLAIM**

The ornamental design for a closure as shown and described.

DESCRIPTION

FIG. 1 is a perspective view of an embodiment of a closure; FIG. 2 is a side view of the closure shown in FIG. 1; FIG. 3 is a side view of the closure shown in FIG. 1, opposite the side view shown in FIG. 2;

FIG. 4 is a side view of the closure shown in FIG. 1; FIG. 5 is a side view of the closure shown in FIG. 1, opposite the side view shown in FIG. 4;

FIG. 6 is a top view of the closure shown in FIG. 1; and, FIG. 7 is a bottom view of the closure shown in FIG. 1. In the drawings, the evenly spaced broken lines show portions of a closure that form no part of the claim; the dash-dot-dash broken lines represent boundaries of the claimed design and form no part thereof.

1 Claim, 3 Drawing Sheets
